UNITED STATES PATENT OFFICE.

ERNEST H. JACOBS, OF SCHENECTADY, NEW YORK, ASSIGNOR TO GENERAL ELECTRIC COMPANY, A CORPORATION OF NEW YORK.

ELECTRIC SWITCH.

1,193,695.

Specification of Letters Patent. Patented Aug. 8, 1916.

Original application filed March 9, 1911, Serial No. 613,376. Divided and this application filed April 26, 1912. Serial No. 693,402.

To all whom it may concern:

Be it known that I, ERNEST H. JACOBS, a citizen of the United States, residing at Schenectady, county of Schenectady, State of New York, have invented certain new and useful Improvements in Electric Switches, of which the following is a specification.

This application is a division of my application filed March 9th, 1911, Serial No. 613,376.

My invention relates to electric switches and more particularly to oil switches, in which the movable contact should have a straight line motion.

In oil switches as usually constructed, the leads of the circuit to be controlled are secured to fixed contacts mounted in suitable insulators. When the circuit is to be closed, the fixed contacts are electrically connected by a bridging contact controlled by operating mechanism which is generally mounted above or to one side of the switch and of which some parts project over the top of the switch between the leads of the circuit to be controlled. The operating mechanism and the parts thereof which extend between the leads are made of metal to secure the necessary strength and therefore the space between the leads of the circuit must be so great that those metallic portions of the operating mechanism which are between the leads will not cause a breakdown from one lead to the other. Many of the parallel motion operating mechanisms for compelling the movable contact to move in a straight line are objectionable because certain parts of the mechanism are in between the leads or the fixed contacts, and the leads of the circuit must be spaced so far apart that the floor space occupied by the switch is too great.

The object of my invention is to provide an improved switch which is particularly adapted for controlling circuits carrying large amounts of energy; in which the movable contact is given a straight line motion by means of a parallel motion operating mechanism mounted to one side of the switch and having an actuating arm of minimum width projecting over the top of the switch between the leads, so that the lateral dimensions of the metallic members between leads

is reduced to a minimum; in which the pivots, links and other bulky parts of the parallel motion mechanism are placed so far away from the live parts of the switch that the mechanism does not have any tendency to cause breakdown from one live part to another; in which the movable contact is positively guided in substantially a straight line so that it works easily and drops away from the fixed contacts quickly and cannot swing out of alignment with the fixed contact; and in which the operating mechanism of the switch is thoroughly protected from the weather and from injury, but may be easily inspected when desired.

Another object of my invention is to provide an operating mechanism which will permit the switch to open independently of the position of the handle or other operating member in case conditions upon the circuit are abnormal when the switch is closed, and which will trip with greater ease and certainty than devices of this kind heretofore used, particularly where the switch is large and the force transmitted through the operating mechanism is great.

My invention will best be understood in connection with the accompanying drawings, which merely for purposes of illustration show some of the various forms in which the invention may be embodied and in which—

Figure 1 is a view partly in section of a form of switch which is particularly adapted to control high potential circuits carrying great quantities of energy and in which the movable contact is automatically released from the handle in case of overload and other abnormal conditions on the circuit; Figs. 2, 3 and 4 are detail views of the mechanism, Fig. 2 showing the parts in the position assumed by them when the switch is closed; Fig. 3 a view of the same mechanism after it has been tripped automatically; and Fig. 4 is a view of the same mechanism in the position ready to again close the switch.

Fig. 1 shows a form of switch embodying my invention and well adapted to control circuits in which the potential is high and in which the amount of energy flowing is great. In this particular form of switch an oil tank 1 containing a sufficient amount of oil

to submerge the contacts of the switch stands upon the floor of the station and is provided with a cover 2, preferably consisting of two portions separated by a comparatively narrow gap. In each of said portions there is an insulator 3 having a central conducting rod with its upper end connected to a lead of the circuit to be controlled and its lower end secured to some suitable form of fixed contact, such as the contact 4 shown in dotted lines and mounted in a pressure retaining chamber which confines the oil put under pressure by the arc and directs the oil against the arc to extinguish it. The circuit is controlled by means of a bridging contact 5 which moves into and out of engagement with the fixed contacts on the lower ends of the insulators 3 and which is carried by an insulating rod 6 with its upper end extending above the surface of the oil in the oil vessel 1. The rod 6 is moved up and down by some suitable form of parallel motion operating mechanism having an arm which extends between the insulators 3 and which is connected at one end to the upper end of the rod 6. In the particular arrangement shown, the force for moving the parallel motion operating mechanism is transmitted to the operating mechanism through a system of interconnected rods and bell cranks from some suitable operating member such as the handles 7 mounted upon any convenient and suitable support such as a panel 8.

In some cases the switch actuating mechanism is mounted upon a support which is independent of the oil tank and contacts of the switch, but is fixed in some suitable relation thereto, so that the operating arm of the mechanism will project between the leads going to the switch and will move between the leads and parallel to them for the purpose of operating the movable contact. In such cases the parallel motion mechanism for moving the operating arm should be as compact as possible so that the floor space occupied by the switch and its actuating mechanism shall be reduced to a minimum. In the preferred construction, illustrated in Figs. 2, 3 and 4, some suitable support 9 is provided on which the various parts of the parallel motion operating mechanism are mounted. In the particular form of mechanism shown, a switch actuating member suitably journaled or mounted on the support 9 and comprising a rock shaft 10 is provided with a rigid extension or arm 11 which forms part of the parallel motion mechanism. To the outer end of the arm 11 is pivoted a link 12 which forms part of the parallel motion mechanism and is pivoted at its outer end to an arm 13 to which the movable contact of the switch is connected and by which the mov-

able contact is actuated. One end of the arm 13 is pivotally connected to a link 14 mounted upon a suitable pivot 15 on the support 9. As the rock shaft 10 is moved the link 14 is swung on its pivot by means of a guiding toggle 16 which is connected through an actuating link 17 to the arm 11. The various parts are so proportioned that as the arm 11 rocks about the rock shaft 10 as an axis, the arm 13 is moved up and down to open and close the switch and owing to the action of the guiding toggle 16, the link 14 and arm 13 are so moved that the end of the arm 13 and the movable contact connected to it, move in a straight line.

During the opening of the switch the movable contact attains a comparatively high velocity and some sort of yielding or resilient stop should be provided to stop the downward movement of the movable contact without causing excessive strains or jars, and also to store up energy which will assist the operator to close the switch. A spring 18 is connected at one end by a pin 19 to the link 12 and is connected at the other end by a pin 20 to the support 9, the parts being so proportioned that as the arm 13 moves downward to open the switch, the spring 18 is put under strain and yieldingly stops the downward movement of the contact. The stretched spring also assists in closing the switch.

The actuating member of the switch mechanism also comprises an arm 21 rigidly secured to the rock shaft 10 and an operating member 22, which is loosely mounted on the rock shaft and is movable independently of the actuating mechanism by an operating handle controlled by the operator.

In many types of switches, the switch mechanism is preferably disconnected from the operating handle or member when the conditions on the circuit are abnormal so that, for instance, it is impossible for the operator to hold the switch closed on over-load. In order to attain this result I provide between the operating member 22 and the arm 21 of the actuating member of the switch mechanism, some form of collapsible connection which normally forms a rigid and positive connection between the two members but which under definite and predetermined conditions will collapse and permit the members to move independently of each other. Various forms of collapsible connections may be used, but the preferred construction is that shown, which is particularly adapted for use where the switch is large and the amount of force to be transmitted through the connection is great. In this preferred form of collapsible connection the operating member 22 is connected to the arm 21 through a normally underset toggle consisting of a link 23 connected to the arm 21 through some suitable lost mo-

tion connection such as a pin 24 which enters a slot in the end of the link 23, so that the link can move to a certain extent independently of the arm 21, and of a second link 25 pivoted to the link 23 to form a normally underset toggle which always tends to collapse. In order that the underset main toggle 23-25 may normally be held rigid, but at the same time will be in condition to collapse upon the occurrence of overload or other abnormal conditions on the circuit, some suitable device such as a sensitive form of locking toggle is provided for holding the main toggle extended. In the particular form of mechanism shown in the drawing, the link 25 extends beyond the pivot 26 and at a point beyond the pivot is provided with a pin 27 on which is mounted one link 28 of the locking toggle. The other link 29 of the locking toggle has one end connected to the middle of the link 28 and the other end mounted on a pivot 30 secured to the operating member 22. The locking toggle 28-29 is also normally underset and is held against collapse by a latch 31 mounted on the pivot 30. The latch 31 has near one end a notch or other suitable means 32 for engaging the free end of the link 28 and near the other end a projection 33, which, when the switch is in the closed position, is in alignment with the core of an electro-responsive device, such as an overload coil or solenoid 34.

In order to facilitate straightening out the main toggle 23-25, the rock shaft 10 is provided with an arm or projection 35 which is connected through a spring 36 to the operating member 22, this spring being so proportioned that it tends to straighten the main toggle 23-25.

Where the movable contact is arrested in its downward movement by a spring buffer, such as the spring 18, there is a tendency for the contact to rebound, and some suitable latching mechanism is provided which will catch the operating mechanism as the switch opens and hold the switch in the open position. It is desirable that the latching mechanism be automatically controlled by the movement of the operating mechanism incident to the closing of the switch, so that the catch will be automatically moved to release the switch as soon as the operator begins to close the switch. In the preferred construction the switch is caught and held open by means of a latch or detent 37 mounted on the support 9 in a position to actuate and engage the end of the arm 21 as the switch opens, this latch being provided with a lug or projection 38, so arranged that as the operator begins to close the switch by moving the operating member 22, the link 23 of the main toggle moves a short distance independently of the arm 21 and during this independent movement the end of the link

engages the lug 38 and forces the latch 37 down, thereby releasing the arm 21 so that the switch is free and can be closed.

When the switch is closed the parts are in the position shown in Fig. 2, where the main toggle 23-25 is prevented from collapsing by the locking toggle 28-29, which in turn is held against collapse by the latch 31. If an overload or any other abnormal condition appears on the circuit the coil 34 is energized, the latch 31 is moved and releases the other end of the link 28 of the locking toggle, whereupon the locking toggle collapses and permits the main toggle to collapse so that the actuating member of the switch can move independently of the main operating member 22, and the parts then move to the position shown in Fig. 3 as the switch opens. In order to close the switch it is necessary that the operator move the operating member 22 in such a way that the members 22 and 21 are again locked in rigid relation to each other, and this result is accomplished by moving the operating member 22 to the position shown in Fig. 4, by which movement the main and locking toggles are straightened out and are held in the extended position by the latch 31 engaging the end of the link 28, whereupon the operating member and the actuating member are rigidly locked to each other and the switch can be closed by means of the operating member 22. If the overload is still on the circuit or if other abnormal conditions appear during the closing of the switch, the coil 34 is energized as the contacts of the switch touch, whereupon the latch 31 is again actuated and the switch opens regardless of the position of the operating handle and of the operating member 22.

My invention may be embodied in other forms than those shown and described, and I therefore do not limit my invention to the precise arrangement disclosed in this application, but aim in the appended claims to cover all modifications which are within the spirit and scope of my invention.

What I claim as new and desire to secure by Letters Patent of the United States, is:

1. In an actuating mechanism for electric switches, the combination of a switch actuating member and an operating member mounted to be movable relatively to each other, a collapsible connection between said members for transmitting force from one member to the other, a locking toggle for normally preventing the collapse of said connection, said toggle comprising a link pivoted at one end to said connection, a second link pivoted to said operating member and to said first link at a point between the ends thereof, and a latch mounted on the pivot of said second link to engage the free end of said first link and thereby normally prevent collapse of said locking toggle.

2. In an actuating mechanism for electric switches, the combination of a switch actuating member, an operating member, a normally underset collapsible main toggle connecting said members, a locking toggle pivoted to said main toggle and to said operating member for normally preventing the collapse of said main toggle, and a latch pivoted on said operating member to engage one of the links of said locking toggle and thereby prevent collapse of both said toggles.

3. In a switch actuating mechanism, the combination of a switch actuating member and an operating member mounted to oscillate independently of each other about a common axis, a normally positive collapsible connection between said members having a lost motion connection with one of said members to permit a limited movement of said connection independently of said member, and a detent mounted to engage said switch actuating member and hold the switch in open position and to be moved into position to release said switch actuating member by movement of said connection incident to closing of the switch.

4. In a switch actuating mechanism, the combination of a switch actuating member and an operating member mounted to rock

about the same axis, a main toggle having one end connected to said operating member and the other end to said actuating member, a locking toggle having one end pivoted to one link of said main toggle and the other end pivoted on said operating member, a latch pivoted on said operating member to coöperate with one of the links of said locking toggle, and means responsive to abnormal conditions on the circuit controlled by the switch for moving said latch and thereby permitting both said toggles to collapse and said members to move relatively to each other.

5. In an actuating mechanism for electric switches, the combination of a switch actuating member, an operating member, a collapsible main toggle connecting said members, a locking toggle operatively related to said main toggle for normally preventing the collapse of said main toggle, and electromagnetic means for controlling the collapse of said locking toggle.

In witness whereof, I have hereunto set my hand this 25th day of April, 1912.

ERNEST H. JACOBS.
